PRECAST BURIAL VAULT

James N. McNabb, Ralph E. Cowan, and William E. Craiglow, Wichita, Kans.

Application April 23, 1932, Serial No. 607,108

5 Claims. (Cl. 72—7)

This invention relates to an improvement in pre-cast burial vaults.

The object of our invention is to provide a burial vault having a positive airtight seal between the cover and vault proper. Another object is to provide a burial vault having a plurality of compartments separated by partitions having ventilation openings therein or around. A still further object is to provide a vault as above described and in which the air therein is caused to circulate through the various compartments by reason of natural heat, as from the sun, being applied to the exposed top of the vault. A still further object of our invention is to provide a burial vault having a bottom and side walls made of a non-moisture absorbing material and a moisture absorbing top or cover therefore for the purpose of absorbing moisture from the air within the vault which is picked up from the body therein and in turn is discharged from the top by evaporation by reason of external heat such as produced by the sun. A still further object is to provide a burial vault which will dispose of moisture introduced into the vault by placing a body therein, and permanently preserving the body in a mummified condition.

All these, and other objects will be more fully described and explained as this description progresses.

Now, referring to the drawings, Fig. 1 is a plan view of our improved burial vault. Fig. 2 is a longitudinal sectional view taken along the line II—II in Fig. 1. Fig. 3 is a transverse sectional view as seen from the line III—III in Fig. 2. Fig. 4 is a plan view of our improved burial vault with the top or cover removed. Fig. 5 is a sectional view as seen looking downward from the line V—V in Fig. 2. Fig. 6 is an enlarged detail sectional view as seen from the line VI—VI in Fig. 4. Fig. 7 is an enlarged sectional detail view as seen from the line VII—VII in Fig. 1.

In the drawings is shown a vault, preferably made of cast concrete, and having integral walls 10, 11, 12 and 13 and bottom 14. These elements 10, 11, 12 and 13 and bottom 14 are made of waterproof concrete, or of concrete overcoated with waterproofing material. It will be understood the concrete in the elements 10, 11, 12, 13 and 14 may be reinforced with any suitable reinforcing material such as metal rods, wire mesh or the like. At 16, 17, 18, 19, 20, 21, 22, 23, 24 and 25 are support elements on which rest a pair of concrete slabs 26 and 27. These slabs 26 and 27 are provided with an upwardly projecting rib 28 and 29 on which the casket A rests. Portions

of the edges of the slabs 26 and 27 are cutaway so that the corners and central portions of the slabs 26 and 27 will rest on the supports 16, 17, 18, 19, 20, 21, 22, 23, 24 and 25 with the corners of the slabs 26 and 27 fitting loosely in the corners and against the sides of the vault and leaving air circulation openings 28', 29, 30, 31, 32, 33 and 34 between the slabs themselves and also between the slabs and the side and end walls of the vault. The slabs 26 and 27 are further provided with air circulation openings 35, 36, 37 and 38.

In the interior side of the wall 10 and near the top thereof is a continuous notch or groove 39 which is adapted to receive and support one edge of a compartment partition slab or a plurality of slabs 40 and 41. The opposite edges of the slabs 40 and 41 rests on a shoulder 42 which is positioned in the interior side of the wall 12 and is opposite and parallel with the groove or notch 39. The portion 43 of the wall 12 above the shoulder 42 is circled or cut away so that the edge of the compartment partition slabs 40 and 41 may be rocked downward to bear on and be supported on the shoulder 42. The compartment partition slabs 40 and 41 are made sufficiently short that they may be placed in position in the vault and leave an air circulation space or opening 44 between the slabs and also a similar air circulation space or opening 45 and 46 at either end of the vault between the end walls of the vault and the adjacent compartment partition slab 40 or 41. At 40y and 41y are holes through the slabs 40 and 41 provided for additional air circulation passages.

The upper edge of the walls 10, 11, 12 and 13 are provided with a continuous shoulder 47 and a portion 48 projecting upwardly above the shoulder 47, the upper face of which is provided with a continuous groove 49. It will be understood that while the groove 49 is shown to be circular in form, it may be square, V shaped or any other desired shape. At intervals around the top of the walls 10, 11, 12 and 13 are holes or pockets 50, the purpose of which will be later explained. In the interior face of the walls 10, 11, 12 and 13 just below the upper edge of the portion 48 is a continuous notch or groove 51.

At 52 is a top cover for the vault. This cover has a convex top surface and is provided with a tablet or marker base 53. The bottom edge of the cover 52 is fashioned to receive and loosely fit the top of the vault walls 10, 11, 12 and 13. At 54 is a portion depending from the cover 52 and continuing entirely around the bottom thereof and being adapted to loosely fit between the walls of the vault. In the outside face of

the portion 54 is a continuous notch or groove 55 which, when the top cover 52 is placed on the top of the walls of the vault, registers with the corresponding groove 51 in the walls of the vault. 5 At 56 is an anchor cast in the cover 52 and is adapted to enter the holes or pockets 50 in the walls 10, 11, 12 and 13, when the cover 52 is placed on the vault, as a means of permanently locking the cover on the vault as will be later 10 described.

As above stated, the top cover 52 is made in a convex shape which will shed water.

In preparing our improved vault for use, it is set in the ground so that the grade line 57 of 15 the ground is at a point approximately midway between the top edge of the cover 52 and the joint between the cover and the walls of the vault. The cover 52 and the compartment division slabs 40 and 41 are removed. The casket 20 A containing the body is then placed in the vault and is supported on the ribs 28 and 29, leaving an air space 58 between the bottom of the casket and the slabs 26 and 27. Then one edge of the compartment partition slabs 40 and 25 41 is placed in the groove 39 and the opposite edges of the slabs are rocked downward until they rest on the shoulder 42 and the slabs are in the dotted position 41a, care being taken to leave the space 44 between the slabs and the 30 spaces 45 and 46 between the slabs and the end walls 11 and 13 of the vault. After having placed the slabs 40 and 41 in position as above described, the joints between the slabs 40 and 41 and the walls 10 and 12 are flushed preferably 35 with a rich cement mixture and allowed to set, whereupon the slabs 40 and 41 and the ribs 40x and 41x function as a stiffening element for the upper portion of the side walls 10 and 12 against earth pressure. The vault is now prepared to receive the top cover 52 by placing 40 preferably a plentiful amount of a rich mixture of cement on the shoulder 47 and the upturned face of the portion 48 filling the groove 49 and the holes or pockets 50. The cover 52 is now 45 placed on the vault with the elements 56 entering the holes or pockets 50 and the cover fitting over the walls as shown in Fig. 7, the weight of 50 said cover forcing any excess amount of cement between the cover and the walls and fill the grooves 51 and 55 and perfectly lock and seal the cover 52 to the walls 10, 11, 12 and 13.

The body in the casket contains an appreciable amount of water or moisture. The process of 55 disposing of this moisture is as follows: The air, sealed within the vault will absorb and pick up the moisture as it is slowly discharged from the body. The sun beating down on the cover 52 causes the cover to become heated, thereby 60 heating the compartment between the cover 52 and the slabs 40 and 41 which causes the air in the compartment containing the casket and the air in the compartment between the slabs 26 and 27 and the bottom 14 of the vault to 65 circulate into the upper compartment whereupon the moisture in the air is absorbed into the cover 52 and evaporated away into the outside air under the heat of the sun. Upon the cooling of the cover 52, such as at night time, the air 70 drops from the upper compartment into the lower compartments and the process above described is again repeated. This process continually repeats itself until all moisture has been removed from the vault and the vault is permanently 75 maintained in a dry condition. It will be under-

stood that all the cast elements of our vault may be re-inforced with any suitable form of re-inforcing material such as iron rods, wire mesh and the like.

There may be instances where it is desirable 80 to bury the vault completely under the ground in which case a moisture absorbing feature different from that above described may be desirable. This feature may be obtained by filling or partially filling the lower compartment of the vault with an antiseptic moisture absorbing material such as slack lime or the like. The partition slabs 26 and 27 are replaced with a solid slab which fits against the side and end walls of the vault and after said slab is placed in the vault it is preferably sealed therein by slushing the joints between the slab and the end and side walls with any suitable material such as a rich cement mixture, asphalt and the like. The slab may be provided with a suitable number of any desirable type of moisture seals or openings to admit any accumulation of moisture from the intermediate chamber to pass into the lower chamber.

Such modifications of our invention may be 100 employed as lie within the scope of the appended claims, without departing from the spirit and intention of our invention.

Now having fully explained our invention, what we claim as new and desire to secure by Letters 105 Patent is:

1. In a burial vault, said vault having a lower, intermediate and upper compartment, partitions between said compartments, the partition between the lower and intermediate compartments 110 being supported on block like elements positioned in the corners at the floor of the vault, the partitions between the intermediate and upper compartments being supported on one side in a notch or groove in one of the side walls of the vault, the 115 opposite side of said partition being supported on a shoulder in the opposite side wall of said vault, the portion of the side wall of said vault, above said shoulder being circled so that the partition may be installed by first placing one edge in said 120 notch or groove in one wall and then rocking the partition slab or slabs downward until their opposite edge or edges rest on the shoulder in the opposite wall, ventilation openings from each compartment to its adjacent compartment, a 125 cover for said vault, and means for the air tight sealing of said cover to said vault.

2. In a pre-cast burial vault, a vault having an upper, an intermediate and a lower compartment, said lower compartment functioning as a container for an antiseptic moisture absorbent material, means for permitting a circulation of air between the upper and intermediate compartments, an air tight division between the intermediate compartment and the lower compartment 135 and means in said air tight division for admitting the passage of moisture from the intermediate compartment to the lower compartment, as and for the purpose described.

3. In a burial vault, said vault having an integral bottom, side and end walls and a separate cover therefor, the upper edges of said walls being deformed for a part of a means for sealing said cover on said vault, the lower edges of said cover being deformed to fit over, around and 145 between the upper edges of the walls of said vault, a continuous groove in the inner side of said walls and adjacent the top edge of the walls, an inner depending portion on said cover and a continuous groove therein, said groove being so positioned 150

- that when the cover is placed on the vault the two grooves will be in alignment with and opposite each other so that in assembling the cover on the vault a liberal amount of a cement mixture 5 may be placed on the upper edges of the vault walls so that when the cover is placed thereon the cement will be forced into the said grooves and when set will form a permanent seal between the walls of the vault and the cover thereon.
- 10 4. In a burial vault as described in claim 3, and strut elements at the top portion of and between the said walls of the vault substantially as shown and described.
- 15 5. In a burial vault, said vault comprising an
- integral bottom, end and side walls and a cover therefor, partitions in said vault, said partitions dividing said vault into an upper, intermediate and lower compartments, said intermediate compartment being large enough to receive and house a casket and corpse therein, and means in said partitions to permit a circulation of air in said vault from the lower compartment through the intermediate compartment into the upper compartment and visa versa substantially as shown and described and for the purpose set forth.
